UNITED STATES PATENT OFFICE.

LEAMAN S. HARVEY, OF WATERBURY, CONNECTICUT.

PENCIL HOLDER AND POCKET CLIP.

Application filed May 29, 1926, Serial No. 112,501. Renewed November 3, 1927.

This invention relates to pencil holders, and more particularly to a combined pencil holder and clip which is adapted to remain attached to the edge of the pocket of the user 5 while the pencil is being used, and which is adapted to hold the pencil when the latter is not in use.

One object of this invention is to provide a pencil holder of the above nature adapted 10 to be formed from a single piece of sheet metal.

A further object is to provide a pencil holder which will be simple in construction, inexpensive to manufacture, easy to manipulate, compact, ornamental in appearance, and very efficient and durable in use.

With these and other objects in view, there has been illustrated on the accompanying drawings, one form in which the invention 20 may be conveniently embodied in practice.

Fig. 1 represents a front view of the pencil holder, showing the clip adapted to project over the edge of the pocket.

Fig. 2 is a side view of the same.

Fig. 3 is a plan view of the sheet metal blank from which the holder is formed up by stamping and bending.

Fig. 4 is a top view of the pencil holder and clip.

Fig. 5 is a transverse sectional view of the same taken along the line 5—5 of Fig. 2, looking in the direction of the arrows.

Fig. 6 is a front view of the pencil holder showing its appearance when attached to the 35 edge of a vest pocket, and with a pencil located therein.

Referring now to the drawings in which like reference numerals denote corresponding parts throughout the several views, the 40 numeral 10 indicates the body portion of the pencil holder, said body portion preferably having a straight top edge. The body portion 10 has a pair of slightly converging strips 11 and 12 depending therefrom at the outer sides thereof, said strips 11 and 12 being preferably of uniform width. When the blank is bent into substantially cylindrical shape, as shown, the strips 11 and 12 will serve as tongues for 45 resiliently engaging against the pencil. In order to enhance the gripping power of the strips 11 and 12, said strips are preferably bent inwardly toward the center of the holder, as clearly shown in Figs. 2 and 4.

The body portion 10 also has depending therefrom a tapered central section or loop

14, within which is a slightly tapered pocket clip 15, the top 16 of said clip 15 being preferably made convex outwardly, and the bottom 17 thereof being concave outwardly, the 60 concave section being provided with a central longitudinal rib 18 for strengthening its construction. In order to facilitate the insertion of the pencil after use, the upper part of the pencil holder is flared outwardly 65 at 19.

In the process of manufacturing the completed device, the stamped-out blank, as shown in Fig. 3, is preferably bent around suitable forms, not shown, into a substantially cylindrical tube. The strips 11 and 12 are bent within the outline of the tube 70 so that the resiliency of the metal of said strips will cause them to clamp the pencil and hold it securely from falling out of the 75 pocket.

In operation, when the user desires to write with the pencil he will remove it from the holder, the latter remaining in the pocket 20. When through using the pencil, 80 the user will insert it, point downward, through the flared opening 19 of the pencil holder, and push it downwardly until it reaches the position shown in Fig. 6.

One advantage of the present invention 85 is that when the blank is formed up into its final shape, the strips 11 and 12 by reason of their tapered construction will not overlap or interfere with each other in any way but will be maintained in a slightly separated position.

A further advantage is that the holder will carry short pencils equally as well as long pencils, and thin pencils as well as thick pencils.

A further advantage of this invention is that when the user has a long pencil in his pocket, there will be no danger of breaking the point of the pencil or having the holding clip slip off of the edge of the pocket 100 when the user bends over. This is for the reason that the pencil will be held by the resilient strips.

Moreover, since the holder always remains in the pocket, it can never become lost, and 105 the edge of the pocket will not wear out due to the constant rubbing as was the case with the former types of clips which were permanently attached to the pencil.

The use of the present invention also 110 facilitates the replacing of a pencil in the pocket, as it is much easier to insert the

pencil in the flared mouth of the holder than to force a clip over the edge of the pocket.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a pencil holder, a body portion bent to cylindrical shape, a central loop and a pair of side tongues depending from said body portion for clamping upon a pencil, and a clip connected to said body portion and located within said loop, said clip and loop being adapted to clamp opposite sides of a pocket for holding said pencil holder thereon while the pencil is being used.

2. In a pencil holder, a body portion bent to cylindrical shape, a central loop and a pair of side tongues depending from said body portion for clamping upon a pencil, and a clip connected to said body portion and located within said loop, said clip and loop being located on the opposite sides of a pocket for attaching the pencil holder thereto, said side tongues converging slightly downwardly whereby overlapping will be prevented.

3. In a pencil holder, a body portion bent to cylindrical shape, a central loop and a

pair of side tongues depending from said body portion for clamping upon a pencil, and a clip connected to said body portion and located within said loop for attaching said holder to the edge of a pocket, said pocket edge being clamped between said clip and said loop, said clip having a concave lower section, and a longitudinal strengthening rib in said concave section.

4. In a pencil holder, a body portion bent to tubular shape, a central loop and a pair of side tongues depending from said body portion for clamping upon a pencil, and a clip connected to said body portion and located within said loop, said clip and loop being adapted to clamp opposite sides of a pocket for holding said pencil holder thereon while the pencil is being used.

5. In a pencil holder, a body portion bent to cylindrical shape, a central loop and a side tongue depending from said body portion for clamping upon a pencil, and a clip connected to said body portion and located within said loop, said clip and loop being adapted to clamp opposite sides of a pocket for holding said pencil holder thereon while the pencil is being used.

6. In a pencil holder, a body portion bent to tubular shape, a central loop and a side tongue depending from said body portion for clamping upon a pencil, and a clip connected to said body portion and located within said loop, said clip and loop being adapted to clamp opposite sides of a pocket for holding said pencil holder thereon while the pencil is being used.

In testimony whereof, I have affixed my signature to this specification.

LEAMAN S. HARVEY.
